[57] **CLAIM**

The ornamental design for a handle for a carpet cleaning machine, as shown and described.

DESCRIPTION

FIG. 1 is a perspective view of a handle for a carpet cleaning machine showing my new design;

FIG. 2 is a side elevational view thereof, the opposite side view being a mirror image thereof;

FIG. 3 is a front elevational view thereof;

FIG. 4 is a back elevational view thereof;

FIG. 5 is a top plan view thereof; and,

FIG. 6 is a bottom view thereof.

The details shown in broken lines in all views are shown for illustrative purposes only and form no part of the claimed design.
